Filed July 20, 1967, Ser. No. 7,898

Term of patent 3½ years

(Cl. D48—20)

FIG. 1

FIG. 4

FIG. 2

The lamp is essentially round and all side elevational configurations are represented by FIGURES 1 and 4.

The dominant features of my design reside in the portions shown in full lines.

I claim:

The ornamental design for a floor lamp, substantially as shown and described.
